UNITED STATES PATENT OFFICE

2,160,567

SWEAT BAND

Willard F. Sterne, Buffalo, N. Y., assignor to
 American Allsafe Company, Inc., Buffalo, N. Y.,
 a corporation of New York

Application September 17, 1937, Serial No. 164,347

4 Claims. (Cl. 2—171)

- This invention relates to improvements in sweat bands or pads designed primarily for use by workers and others for absorbing head-perspiration.
- 5 It has for one of its objects to provide a sweat band of this character which is simple, durable and inexpensive in construction and which effectually absorbs perspiration.
- Another object of the invention is to provide 10 a sanitary sweat band which is adapted to be readily cleaned and sterilized and which effectually frees the eyes of sweat and other sweat-laden matter and eliminates steamed-up and foggy goggles.
- 15 A still further object is to provide a sweat-absorbing head band which is designed to afford comfort to the wearer and adapted to fit any-sized head snugly and firmly and which is free of hooks, buckles or other fastenings.
- 20 In the accompanying drawing: Figure 1 is a perspective view of the sweat band applied to the head of a wearer. Figure 2 is a detached perspective view thereof. Figure 3 is an enlarged cross section taken on line 3—3, Figure 2.
- 25 Similar characters of reference indicate corresponding parts throughout the several views.
- In the preferred embodiment of the invention shown in the drawing, the same consists of an absorbent pad or member 10 of substantially 30 rectangular form to fit or engage the forehead of the wearer and an elastic attaching band 11 applied to the pad for fitting about or encircling the wearer's head to firmly and snugly hold the pad in absorbing contact with the forehead.
- 35 The attaching band is preferably endless and, being elastic, readily adapts itself to different head-sizes without resorting to uncomfortable fastening clasps, buckles and the like, and permits of the ready application and removal of 40 the pad to and from the head. As shown in the drawing, the elastic band overlies and extends over the front or outer face and from end to end of the absorbent pad 10 and while free to move lengthwise or slide freely from end to end of the pad, it is effectually held against transverse displacement by retaining loops 12, also preferably 45 of elastic material, secured to the pad by staples 13 or like fastenings. By this relative arrangement of pad and attaching band, the pad is held closely and snugly to the forehead in absorbing contact therewith to intercept perspiration and other foreign matter carried by it and there is no strain whatever on the pad, the strain being wholly absorbed by the attaching band.
- 50 The pad 10 is made of a tough, cellular, sponge-like material which is soft and pliable and of high sweat-absorptive qualities, and which ef- fectually resists chemical action of sweat and grease and is not subject to shrinking or stretching.
- 5 Before applying this sweat band, it is preferably dipped in cool water and squeezed to remove the excess moisture. When worn it effectually absorbs the perspiration and prevents it pouring into the eyes of the wearer, promoting clear vision at all times and preventing accidents due to faulty vision occasioned by perspiration. Furthermore, this sweat band is particularly useful for those workers who are obliged to wear goggles, and in this connection steaming-up and fogging of the goggles is eliminated. Also, the band is durable and comfortable, easily applied 10 and removed, it affords a sense of coolness to the wearer, it can be easily washed and sterilized and always kept sanitary, and it is inexpensive.
- I claim as my invention:
1. A device of the character described, comprising a sweat-absorbing pad of cellular, sponge-like material for engagement with the forehead of a wearer, an elastic head-engaging band applied thereto and extending over the front face thereof for retaining the pad in close contact with the forehead, and means for establishing a slip-like connection between said pad and said band to permit independent expansion and contraction of such parts relative to each other. 20
2. A device of the character described, comprising a sweat-absorbing pad of a cellular, sponge-like material and adapted for engagement with the forehead of a wearer, loops of elastic material applied to the front face of said pad, and an endless, elastic head-attaching band overlying the front face of the pad from end to end thereof and in sliding retaining engagement with said loops. 30
3. A device of the character described, comprising an elastic head-engaging band and a sweat-absorbing pad of cellular material contiguously overlying a portion of the band and containing loops interfitted with said band to permit of independent absorptive expansion and contraction of the pad relative to the band, and an independent expansion and contraction of the band relative to the pad. 40
4. A device of the character described, comprising a circumferentially adjustable head-engaging band, and a sweat-absorbing pad of cellular material having guide means thereon for connecting said band thereto against relative lateral displacement and permitting a free independent longitudinal displacement of such parts relative to each other. 50
